UNITED STATES PATENT OFFICE.

THEODOR HAGEN, OF TRIPOLI, IOWA.

CAR-COUPING.

SPECIFICATION forming part of Letters Patent No. 555,506, dated March 3, 1896.

Application filed October 5, 1895. Serial No. 564,784. (No model.)

To all whom it may concern:

Be it known that I, THEODOR HAGEN, a citizen of the United States, residing at Tripoli, in the county of Bremer and State of Iowa, have invented a new and useful Car-Coupling, of which the following is a specification.

This invention relates to improvements in car-couplings.

The object of the present invention is to improve the construction of car-couplings, and to provide a simple and efficient one capable of coupling automatically and adapted to be readily uncoupled without going between cars.

Another object of the invention is to enable a link to be supported in a horizontal position for guiding it into the mouth of a draw-head and enable the car-coupling to couple with the ordinary pin-and-link car-couplings.

The invention consists in the construction and novel combination and arrangement of parts hereinafter fully described, illustrated in the accompanying drawings, and pointed out in the claims hereto appended.

In the drawings, Figure 1 is a perspective view of a car-coupling constructed in accordance with this invention and shown applied to a car. Fig. 2 is a central vertical longitudinal sectional view of the draw-head, the spacing-block being in position for shortening the link to enable the car-coupling to be coupled with the ordinary pin-and-link draw-head without bending or otherwise injuring the link. Fig. 3 is a transverse sectional view. Fig. 4 is a sectional view taken longitudinally of the draw-head and illustrating the construction of the spring-actuated link-engaging bars and showing the same in engagement with a link. Fig. 5 is a detail perspective view of one of the link-engaging bars.

Like numerals of reference designate corresponding parts in all the figures of the drawings.

1 designates a draw-head, having a longitudinal link-opening and composed of upper and lower sections 2 and 3 suitably bolted and interlocked to secure the necessary solidity, and within the draw-head is arranged a pair of link-holding bars 4, adapted to engage the upper faces of the sides of a link 5 to hold the latter in a horizontal position for

guiding it in the mouth of a draw-head. The link-holding bars 4 have their front portions curved upward and their rear terminals are 55 provided with eyes or openings through which passes a transverse pivot 5^a, which hinges the bars 4 to the draw-head and permits them to move independently of each other. The upper section of the draw-head is provided with longitudinal recesses 6 to receive the link-holding bars, and the front or outer portions of the recesses are enlarged to receive the curved portions of the bars 4. These bars are provided at their outer side edges with depending flanges 7, which receive the link between them and prevent the same from moving laterally out of engagement with them, and the lower section of the car-coupling is provided with recesses 8 to receive the flanges 7. 70

The link is yieldingly engaged by the bars 4, which are pressed downward by spiral springs 4^a, located above the bars in sockets or recesses of the upper section of the draw-head and having their lower ends engaging 75 the upper faces of the bars and receiving studs or projections thereof.

The link is engaged by a coupling-pin 9, arranged in a slot 10 of the draw-head and provided with a longitudinal slot 11, through which passes a pivot-pin 12. The slot 10 of the draw-head is substantially triangular and its front wall is vertical, and the coupling-pin when in a vertical position is adapted to bear against the front wall of the slot 10. The lower section of the draw-head is provided with a central longitudinal recess 13 to receive the lower end of the coupling-pin, and the slot 10 of the upper section permits the coupling-pin to swing rearward or inward to enable a 85 link entering the draw-head to pass it and be engaged by the same to effect the operation of coupling. When the link is in engagement with the coupling-pin the lower end of the latter bears against the front wall of the 90 central recess 13 of the lower section of the draw-head.

The slot 12 of the coupling-pin permits the latter to move vertically to effect the operation of uncoupling, and the coupling-pin is 100 maintained normally in a vertical position by a spiral spring 14 mounted on top of the draw-head and located in rear of the coupling-pin, and connected at its front end to the upper

end of the same and at its rear end to the draw-head. The spring 14 is arranged within a casing 15, which is substantially U-shaped or semitubular, which is secured to the draw-head at opposite sides thereof and extends over the top of the same.

The operation of uncoupling is performed from the sides of a car 16 by a horizontal rock-shaft 17 journaled on the car in suitable bearings thereof and provided with a central arm 18, connected by a chain with the upper end of the coupling-pin, and when the rock-shaft is rotated and the arm 18 swung upward the coupling-pin is lifted out of engagement with the link. The rock-shaft may be provided at each end with a handle to enable it to be operated at either side of the car, and a rod 19, which extends to the top of the car, is connected with the rock-shaft and is adapted 20 to rotate the same and enable the coupling-pin to be lifted from the top of the car. The rod is arranged in a guide 20 and is provided at its lower end with an eye receiving the rock-shaft, and the latter is provided with a 25 projection or arm 21 arranged in rear of the rod 19, whereby when the rod is swung inward the rock-shaft will be rotated.

The shank or draw-bar of the draw-head is slidingly mounted on the car in suitable 30 guides or ways, and the draw-head is provided at its top with an enlargement 22, between which and the car is interposed a spiral spring 23, arranged partially within the casing 15 and adapted to form a cushion to protect 35 the parts in coupling.

The link is slightly longer than that employed in the ordinary pin-and-link car-couplings, and to prevent any liability of the link being bent or otherwise injured when used to 40 couple the improved draw-head with the ordinary pin-and-link draw-head a spacing-block 24 is employed and is interposed between the two draw-heads. The spacing-block is rectangular and is provided with a 45 link-opening 25, and it has at its top a pair of hooks 26 adapted to engage the draw-head to assist in supporting it in position. The block fits on the link and thereby shortens the same, and it is designed to be connected to the car 50 by a chain or other suitable means to prevent it from being lost.

It will be seen that the car-coupling is simple and comparatively inexpensive in construction, that it is capable of automatic coupling, and that it may be readily uncoupled without going between cars, and that it is adapted to hold a link in a horizontal position to guide it into the mouth of the draw-head.

Changes in the form, proportion, and minor 60 details of construction may be resorted to

without departing from the principle or sacrificing any advantages of the invention.

Having thus described my invention, what I claim is—

1. In a car-coupling, the combination of a draw-head, a link, means for engaging the link, and a pair of longitudinally-disposed link-holding bars located within the draw-head at opposite sides thereof, independently hinged at their inner ends to the same and 70 having their front ends curved upward, said link-holding bars being adapted to engage yieldingly the upper face of the link and capable of independent movement, substantially as described. 75

2. In a car-coupling, the combination of a draw-head means for engaging a link, longitudinally-disposed link-holding bars independently hinged at their inner ends to the draw-head, and having their outer ends 80 curved upward, and provided at their sides with depending flanges, and springs for forcing the bars downward into engagement with the link, substantially as described.

3. In a car-coupling, the combination with 85 a car of a draw-head mounted on the car and provided in advance of the same with a shoulder or enlargement, a spring arranged at the top of the draw-head, and interposed between the car and the enlargement, a vertically-mov- 90 able coupling-pin, having a longitudinal slot, a pivot passing through the slot hinging the coupling-pin to the draw-head, a spring connected with the coupling-pin and the draw-head and arranged in rear of the former, and 95 the casing mounted on the draw-head, and forming a housing for the said springs, substantially as described.

4. In a car-coupling, the combination of a draw-head, an elongated link, and a spacing- 100 block arranged in advance of the draw-head, and provided with a link-opening, and having supporting devices detachably engaging the draw-head, substantially as described.

5. In a car-coupling, the combination with 105 a draw-head, and an elongated link, of a spacing-bar arranged on the link in advance of the draw-head, shortening the same and provided at opposite sides with hooks detachably engaging the draw-head at the front thereof 110 and suspending the block from the top of the same, substantially as and for the purpose described.

In testimony that I claim the foregoing as my own I have hereto affixed my signature in 115 the presence of two witnesses.

THEODOR HAGEN.
